UNITED STATES PATENT OFFICE.

GEORGE A. COATS, OF PHILADELPHIA, PENNSYLVANIA.

PAVEMENT HEATER.

Application filed March 21, 1925. Serial No. 17,195.

The object of my invention is to operate a pavement heater by mounting the necessary equipment upon a standard or conventional tractor, consisting of a suitable frame which supports the various coacting elements including a blower fan to blow the heated air through the furnace or combustion chamber onto the pavement to be heated, said fan being operated by the power taken from what is known as the "power take off" of the tractor which can be driven directly or from a countershaft connection, while in addition to the fan blower, a fuel oil pump is also operated from the same driving mechanism or source of power.

When it is necessary to move the heater from one location to another, when using the power from the "power take off", the action of disengaging the clutch and changing gears necessitates a slowing down or partial stoppage of the blowing member, which interferes with the complete combustion otherwise maintained in the combustion chamber or furnace, and causes more or less smoke, which condition I obviate by inserting a suitable valve in the fuel line and connecting it with the lever used for raising the hood in such a manner, as to shut off or diminish the supply of fuel oil at the time of raising the hood thereby preventing imperfect combustion and the production of smoke during the period of changing gears or moving the equipment from one location to another. My novel collocation of the hood raising mechanism, and the simultaneous control of the fuel supply to the combustion chamber, results in a novel mechanism wherein the fuel supply is automatically controlled by the operator without any attention on his part simultaneously with the actuation of the hood, so that no noticeable quantity of smoke or fumes escape from the hood when the latter is raised or during the shifting of gears or the transferral of the apparatus from one location to another.

To the above ends my invention consists of the novel construction of hood actuating mechanism, connected to the control of the means for supplying fuel to the combustion chamber, in such a way that the fuel supply is automatically controlled or reduced simultaneously with the elevation of the hood, whereby the creation of undue smoke or fumes is obviated, during the shifting of gears or moving of the apparatus from one location to another.

It further consists of a novel construction of hood actuating mechanism, counterbalancing devices therefor, and connections therefrom to the valve in the fuel line, whereby the latter is automatically actuated simultaneously with the actuation of the hood.

It further consists of novel means for driving the fuel pump and blower from the "power take off" of the tractor.

It further consists of a novel detachable frame for a tractor, adapted to carry a pavement heater and its adjuncts.

It further consists of a novel manner of actuating the hood of the pavement heater and novel means for counterbalancing the weight thereof.

It further consists of novel features of construction and advantage all as will be hereinafter described and pointed out in the claims appended hereto.

For the purpose of illustrating my invention, I have shown in the accompanying drawings forms thereof which are at present preferred by me, since they have been found in practice to give satisfactory and reliable results, although it is to be understood that the various instrumentalities of which my invention consists can be variously arranged and organized and that my invention is not limited to the precise arrangement and organization of these instrumentalities as herein shown and described.

Fig. 1 represents a side elevation of a pavement heater, and its adjuncts, embodying my invention.

Fig. 2 represents a diagrammatic view of the mechanism driven from the power take off for driving the fuel pump and blower.

Similar numerals of reference indicate corresponding parts.

Referring to the drawings:—

In carrying out my invention, I install upon a conventional or standard tractor or similar self-propelled vehicle 1, a novel supporting frame 2, the same comprising a U-shaped member or beam 3, preferably of angular shape in cross section, and comprising the uprights 4, and the bottom member 5. The frame 3 is placed against the front pendant portion 6 of the tractor, and secured in position by the bolt 7 or the like, which passes through the plate 8, and through the bifurcations 9 of the tractor frame and is secured in position by the pin 10 or the like. The upper ends of the up-

rights 4, are bolted, riveted or otherwise secured at 11 to the front ends of the upper beams 12, which are oppositely arranged in parallelism and in the same horizontal plane, 5 said upper beams having the forward extension 13, which projects forwardly beyond the uprights 4, the front ends of said extension 13 being tied together by the transverse front angular plate or angle iron 14. 10 The lower beams 15 are composed of the lower horizontal portions 16, which are continued to form the forwardly upwardly inclined portions 17 whose upper ends are secured by welding or otherwise at the points 15 18 to the front bottom portions of the extensions 13. The rear portions of the beams 12 and 16 are joined and braced by the uprights 19, whose bottom flanges or feet 20 are bolted or riveted to the top flanges 21 of 20 the lower beams 15, while the upper ends of said uprights are welded or otherwise secured at the points 22 to the rear ends of the upper beams 12. The gussets 23 may also be employed at the points seen in Figs. 25 1 and 3 to give further strength and rigidity to the frame. 24 designates the top transverse brackets, which are suitably secured to the upper beams 12. The intermediate portion of the frame 2 is secured to the tractor 30 body by the straps or connections 25, as will be understood from Fig. 1. The elongated combustion chamber 26 is supported on the transverse brackets 24, and its front end discharges into the conduit 27, which leads 35 the hot gases and products of combustion into the hood 28, which is supported by means of the connections 29, whose upper ends are connected to the lower arms 30 which are mounted on the shaft 32, which 40 is provided with the upper arm 31. The counterbalancing spring 33 has one end connected to the adjustable fixed point 34, while its front end is connected to the upper arm 31 at the point 35, which is a little distance 45 above the fulcrum point 32, whereby the tension of the spring is effectively applied at the desired point. 36 designates a link having its front end connected to the upper portion of the arm 31, while its rear end is 50 connected to the hand lever 37, which is fulcrumed at the point 38 upon the ratchet plate 39, whose teeth are engaged by the manually operated pawl 40. 41 designates a link having its front end connected to the lever 37 and its rear end connected to the arm 42 of the two way valve 43, in the fuel discharge pipe 44. 45 designates the fuel tank, which is mounted on the rear of the beams 15, and provided with the suction pipe 60 46 having the valve 47, therein, said suction pipe leading to the pump 48. The fuel discharge pipe 44, leads to the valve controlled burner 49, which is positioned at the rear end of the combustion chamber 26. 50 designates the blower conduit which leads from

the blower 51, to the rear of the combustion chamber 26, and conveys the necessary supply of air to the burner to promote combustion. The fuel pump 48 is preferably a rotary pump of any conventional type and 70 the blower 51 is also any standard blower and requires no further detailed description. The pump shaft 52 and the blower shaft 53 may be driven by any suitable mechanism from the power "take off" shaft 54 of 75 the tractor, and in the present instance, I have shown the power therefrom as being transmitted to the sprocket wheel 55 of the shaft 56, by the sprocket chain 57. Power is transmitted from the shaft 56, by the chain 80 57, to the sprocket wheel 58 on the shaft 52. From the shaft 56, power is transmitted by the chain 59, wheel 60 and chain 61, to the sprocket wheel 62 on the blower shaft 53. It will be evident that other equivalent 85 means for driving the pump and blower from the power take off 54 may be employed, and that the fuel tank, pump, and blower may be secured in position upon the frame 2 in other ways than that shown. The rear 90 of the frame 2 may be secured upon the rear axle housings in any suitable manner, as by the yokes 63 and nuts 64 seen in Fig. 1.

The hooks 65 at the upper front portion 95 of the frame 2, permit the upper ends of the connections 29 to be attached thereto, whereby the strain upon the hood operating connections is removed.

The operation is as follows:—Through the medium of the power transmission devices, 100 driven from the "power take off" 54, the fuel pump 48 and the blower are operated in unison, and the hot gases and products of combustion are conveyed through the combustion chamber to the hood, and under normal operating conditions, there is no smoke or fumes rising from the hood to a noticeable extent. When, however, the operator reduces his speed, as is customary in shifting gears, as when the apparatus is moved from 105 one location to another, the speed of the blower decreases and where the fuel supply is not checked, or controlled as in my invention, there is liable to be an excess of smoke or unconsumed particles of combustion is- 110 suing from the hood, when the latter is raised. In my present device, when the operating lever 37 is pulled rearwardly, the arm 42 of the valve 43 is actuated to partially close said valve thereby diminishing the supply of fuel to the burner 49, so that the proportions of the commingled air and fuel under these conditions, will be such 115 that a substantially perfect combustion takes place, and there will be no excess of smoke and fumes issuing from the raised hood. The fuel valve closing operation is entirely automatic, requires no attention on the part of the operator, and occurs simultaneously 120 with the actuating of the lever 37 and the 125 130

raising of the hood, whose weight is counterbalanced by the spring 33.

It will now be apparent that I have devised a novel and useful construction of pavement heater which embodies the features of advantage enumerated as desirable in the statement of the invention and the above description and while I have in the present instance shown and described the preferred embodiments thereof which have been found in practice to give satisfactory and reliable results, it is to be understood that the same are susceptible of modification in various particulars without departing from the spirit or scope of the invention or sacrificing any of its advantages.

Having thus described my invention what I claim as new and desire to secure by Letters Patent, is:—

20 1. In a pavement heater, a combustion chamber and a hood therefor, means for actuating said hood, a fuel supply for said combustion chamber, and connections common to said hood actuating means and fuel

supply, whereby the latter is automatically 25 controlled simultaneously with the actuation of said hood.

2. In a pavement heater, a combustion chamber and a hood therefor, means for actuating said hood, a counterbalancing spring 30 having one end attached to said hood, actuating means for counterbalancing the weight of said hood, a fuel supply for said combustion chamber, and connections common to said hood actuating means and fuel supply, 35 whereby the latter is automatically controlled simultaneously with the actuation of said hood.

3. In a pavement heater, a supporting frame, a combustion chamber and hood carried thereby, a burner in said combustion chamber, a fuel supply pipe for said burner, a valve in said fuel supply pipe, means for raising and lowering said hood, and a connection from said hood actuating means to 40 said valve, whereby the latter is closed and opened during actuation of said hood.

GEORGE A. COATS.
